UNITED STATES PATENT OFFICE.

BURT A. PETERSON, OF ROCKFORD, ILLINOIS, ASSIGNOR TO BARBER-COLMAN COMPANY, OF ROCKFORD, ILLINOIS, A CORPORATION OF ILLINOIS.

METHOD OF MAKING TYING BILLS FOR KNOTTERS.

Original application filed April 1, 1920, Serial No. 370,396. Divided and this application filed August 15, 1924. Serial No. 732,142.

The invention has general reference to knot-tying devices commonly used in the textile arts for uniting the ends of thread or yarn, and it has more special reference 5 to the tying bill of the knot-forming mechanism.

The object of the invention is to provide a novel method of constructing a tying bill, which reduces the cost of manufacture and 10 at the same time produces a bill which accomplishes effectually the purposes for which it is intended.

In the accompanying drawings Figure 1 is a vertical sectional view through a knotter having a tying bill constructed in accordance with my invention.

Fig. 2 is a fragmentary vertical sectional view illustrating one stage in the construction of the bill.

Fig. 3 is a vertical sectional view showing the major portion of the bill in its completed form.

Fig. 4 is a fragmentary vertical sectional view illustrating the parts of the complete bill in assembled relation.

The knotter selected for purposes of illustration comprises briefly an annular or cylindrical casing 10 having a tying bill 13 rotatably supported therein through the 20 medium of a spindle 14. The latter is journaled transversely of the casing and has a gearing connection with a drive element 15 also enclosed within a casing. In the peripheral wall of the casing there is provided a bearing 20 in which is journaled one end of the spindle, and diametrically opposite said bearing and secured within the casing is a member 21 providing a bearing for the opposite end of the spindle.

40 The casing is, in practice, provided with a suitable support (not shown) such that the casing is capable of being rotated as through the medium of the thumb lever 17 rigid therewith, and the driving element 15 is made stationary with reference to said support. On the exterior of the casing, adjacent the tying bill, is a thread clamping device 16 which is also made stationary with respect to said support. Thus in the oscillation of the casing, the tying bill moving bodily therewith, swings with reference to the thread clamping device. For a more detailed description of the knotter construction reference is made to my copending

application Serial No. 370,396, filing date 55 April 1, 1920, of which this application is a division.

The tying bill 13 comprises a stationary clamping jaw 27 rigid with the spindle 14 and carrying a pivot pin 28 upon which is 60 mounted a movable shearing and clamping jaw 29 coacting with the jaw 27 and also with a stationary shearing member 30 commonly termed a "bill spring." The lower portion of the movable jaw 29 is shaped to 65 provide a cam wing 31 which is adapted to coact with a cam barrel 22 (Fig. 1) formed in the member 21, secured to the inner peripheral wall of the casing 10. In the rotation of the spindle 14 the wing 31 engaging 70 with the cam barrel operates the jaw 29 relative to the jaw 27 and the bill spring 30 to effect a clamping and shearing of the thread or threads held thereby, as is well understood in the art.

75 In accordance with my invention the stationary clamping jaw 27 of the tying bill and the shaft or spindle 14 are formed integral from a single piece of drill stock. Thus one end of this piece of stock is 80 initially provided with a longitudinal bore 32 therein and then the upper portion of the bored end of the stock is reduced in diameter by swaging as shown at 33 (Fig. 2). Next the reduced end is bent at substantially right angles to the axis of the stock to form the stationary clamping jaw 27 and a supporting shank 27^a therefor. One side of the reduced portion is now cut away to reduce the thickness by substantially one-half as shown in Fig. 3, so as to provide a flat bearing surface for the movable shearing and clamping jaw 29. To complete this portion of the bill the upper edge of the jaw 27 is ground as at 27^b to 95 provide a rounded clamping edge; and the pin 28 is mounted in the inner end of the jaw 27, it being observed from Fig. 4 that the latter provides ample thickness for a firm and rigid mounting of the pin.

100 In cutting away the side of the stock as above described an opening into the lower end of the bore 32 is provided, and this open end of the bore is adapted to receive the lower end of the bill spring 30 while the upper end thereof is held by the pin 28, the latter being provided with a suitable opening 36 for receiving the pin. To insure

that the bill spring shall not become disengaged from the pin the latter is slightly elongated and the portion of the bill spring surrounding the pin is struck out as shown 5 at 37 (Fig. 4).

Preferably the wall of the bore 32 upon diametrically opposite sides thereof is shaped at its upper ends at 34 and 35 respectively (Fig. 4) to provide opposed bearing surfaces for the opposite sides of the 10 lower end of the spring. These coat to force the upper end of the spring into holding engagement with the movable jaw 29.

Substantially centrally of the spindle 14, 15 it is provided with an annular groove 45 adapted to receive the inner end of a stud 44 carried by the casing and serving to hold the spindle in position in the casing in the manner fully set forth in my said copending 20 application. The lower end of the spindle is cut to form a pinion 46 adapted to mesh with a gear segment 47 carried by the driving element 15.

It will be observed that I have produced 25 a method of making knot-tying bills which materially simplifies the manufacturing operation, so that the cost of construction is reduced to a minimum. Moreover the construction insures that the parts of the bill shall be capable of being readily detached 30 for purposes of renewal, while in operation they are firmly held in position.

I claim as my invention:

1. The method of making a tying bill for 35 knotters which consists in drilling the upper end of a piece of solid stock to form a tubular upper portion, reducing the upper end of said tubular portion, and shaping said reduced portion to provide a support 40 having a flat surface disposed substantially in the plane of the longitudinal axis of the spindle, upon which to mount the bill spring and the clamping and shearing member, with the lower end of the spring entered 45 into the tubular upper end of the spindle.

2. The method of making a tying bill for knotters which consists in reducing the upper end of a hollow spindle by which the 50 bill is to be carried, and shaping the upper end of said reduced portion to provide a support having a flat surface disposed substantially in the plane of the longitudinal axis of the spindle, upon which to support a bill spring and a clamping and shearing member, with the lower end of the bill spring 55 entered into the upper end of the spindle.

3. The method of making a tying bill for knotters which consists in drilling the upper end of a shaft or spindle by which the 60 bill is to be carried to form a tubular upper

portion, reducing the upper end of said tubular portion, shaping said reduced portion to provide a support having a flat surface disposed substantially in the plane of the longitudinal axis of the spindle, upon which 65 to support a bill spring and a clamping and shearing member with the lower end of the bill spring entered into the tubular upper end of the spindle, and shaping the tubular portion of the spindle to provide opposed bearing surfaces adapted to frictionally hold 70 the bill spring in position.

4. The method of making knot-tying bills which consists in forming the upper end 75 of a shaft or spindle in the shape of a tube, flattening one end of the tube, bending the flattened end at substantially right angles to the axis of the tube, and cutting away one side of such flattened end whereby to open the lower end of the tube to receive the 80 lower end of the bill spring.

5. The method of making a tying bill which consists in drilling a piece of stock to form a tubular end, flattening the tubular end and bending the same at right 85 angles, and cutting away one side of the flattened tube to form a stationary jaw having a flat bearing surface for the movable jaw of the bill, and to provide an opening into the tube adapted to receive the lower end 90 of the bill spring.

6. The method of making the stationary clamping jaw of a tying bill, which consists in drilling the end of a piece of stock to form a longitudinal bore therein, flattening 95 the said tubular end, bending said end at substantially right angles, and cutting away one side of the flattened end to form the clamping jaw and provide a bearing surface 100 for the movable jaw of the bill.

7. The method of making a tying bill for knotters which consists in forming the upper end of a shaft or spindle tubular, flattening the tubular portion, cutting away one side of the flattened portion to provide a flat 105 surface extending in a direction axially of the spindle so as to provide a support for a movable clamping and shearing member, and shaping the said tubular portion to provide two opposed surfaces spaced apart axially of the spindle and acting upon a bill spring entered into the tubular portion and between said opposed surfaces so as to yieldably force the other end of the bill spring 110 toward said flat surface and hold the clamping and shearing member in position.

In testimony whereof, I have hereunto affixed my signature.

BURT A. PETERSON.
